UNITED STATES PATENT OFFICE.

CHARLES M. WEIMER, OF BROWNFIELD, PENNSYLVANIA.

BIT SHARPENING MACHINE.

Application filed March 24, 1924. Serial No. 701,345.

This invention relates to bit sharpening machines.

In the operation of cutter bit sharpeners the cutting portion of the bit during the forming or sharpening operation is materially cooled while the shank portion thereof remains at a substantially high working temperature, this being due to the fact that the cutting portion is usually tapered and much thinner and also comes into contact with substantially cold dies. Accordingly, when the bits are plunged directly into a tempering bath upon discharge from the machine the bit portion will not be properly tempered due to being relatively cold. In order to obtain a proper temper it has heretofore been necessary to reheat the bits before being plunged into the tempering bath. It has been found that the heat retained in the shank of the bit is sufficient to raise the temperature of the cooled bit portion if sufficient time is allowed for the redistribution of the heat. It is an object of my invention to provide a bit sharpener having improved means for insuring a more uniform distribution of heat in the bit before it is tempered. A further object is to provide improved means for temporarily holding a bit after it is formed or sharpened until the cutting portion thereof has absorbed enough heat from the body portion of the bit so that the bit can be dropped directly into a tempering bath. A still further object is to provide improved bit control means which will cooperate with some usual operating lever or means that controls the operation of some other member of the machine, thereby enabling these results to be obtained without extra effort on the part of the operator.

In the accompanying drawings I have shown for purposes of illustration one form which my invention may assume in practice.

In these drawings,—

Fig. 1 is a side elevation of my improved sharpening device.

Fig. 2 is a front elevation, parts of which are broken away to show details of construction.

Fig. 3 is a vertical longitudinal section taken substantially on line 3—3 of Fig. 2.

In the illustrative form of my invention I have shown the same embodied in a bit sharpener comprising a main frame 1 supported at its front and rear ends by legs 2 and 3, while carried thereby is a combined

pulley and flywheel 4 adapted to reciprocate the movable element of the bit forming means 5 as by any suitable means such as a crank and connecting rod pivoted at 6 to 60 the member 5. More specifically, the arrangement of the bit forming means comprises a body portion 7 slidably mounted within suitable guideways formed in the sides of the main frame 1 and having a member 8 pivoted thereon as at 9. Pivotally mounted upon the member 8 is a clapper box 10 carrying a die roller 11 at its lower end thus allowing the roller to swing outwardly on reverse movement of the member 5 while adapted to be held in fixed position on forward movement thereof as by abutting the member 8 at 12. In order to allow the member 8 to yield against excessive forces to prevent injury thereof, I have provided a yieldable spring 13 seated within a recess 14 formed in the member 7 and abutting at its upper end a screw 15. A bolt 16 may be used for adjustably limiting the downward movement of the roller 11 80 caused by the spring 13.

Cooperating with the grooved roller 11 are stationary dies generally indicated at 17 and adapted to support a bit blank 18 which rests against an inclined surface 19 formed on a longitudinally adjustable member 20 actuated by any suitable means such as a rack and gear segment 21. Upon operation of the latter, bit 18 will be forced upwardly to further engage the roller 11. When the bit is completely formed, suitable means are provided for discharging the same which comprises a transversely movable member 22 having a longitudinal locking groove 23 adapted to cooperate with the forward portion of the member 20 which carries the inclined surface. Thus, by moving the member 20 rearwardly, the discharging die portion 22 may be moved laterally by any suitable means such as a rod 24 pivoted to a control lever 25 mounted upon the side of the machine. Upon discharge of the bit, the same will drop into a chute 26 which is closed at its outer end by a gate 27 pivoted at its upper end as at 28 while the lower end thereof is held in abutting engagement with the chute 26 by a spring 29. Any suitable means can be used for opening the gate 27, herein shown as comprising a lever 30 to which is attached a suitable flexible member 31 riding over a guide pulley 32 and fixed to a foot treadle 33. This foot treadle controls

a suitable clutch mechanism 34 for controlling movement of the movable die element 5. It will of course be understood that the gate 27 may be controlled by being connected to any other suitable means such as the discharge lever 25 to obtain the same effect of holding the bit within the chute a sufficient length of time to allow the cooled cutting portion of the bit to absorb enough heat from the body so as to be at the proper temperature for discharging into a suitable tempering bath 35 disposed immediately below the end of the chute 26.

In the operation of my device a blank will 15 be inserted in the die and the clutch 34 thrown into engagement by pressing down upon the treadle 33 to cause continued reciprocation of the roller 11 until the bit has been formed, after which the treadle will 20 be released and the lever 25 actuated to cause lateral displacement of the member 22 to eject the formed cutter bit 18 into the chute 26. It will be noted that during this ejection operation the gate 27 will be closed as the 25 treadle 33 will be in an upward position and the ejected bit will come to rest against the gate 27. While the bit remains in such a position the operator will be placing another blank in the dies 17 and by the time the 30 treadle 33 is pressed to cause operation of the roller 11 the bit within the chute will have had its heat redistributed to the cutting portion. Thus, upon pressing the treadle to cause operation of the roller 11, the bit in 35 the chute will be allowed to drop into a receptacle containing a tempering bath. It will thus be seen that I have provided an automatic means for tempering cutter bits formed by a sharpener which relieves the operator of a great deal of trouble and, further, does away with reheating the bits before tempering such as is necessary when the bits are merely dropped on to the floor from the chute, as well as the ineffective tempering obtained where the bit is at once dropped into the tempering bath.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. The combination comprising a bit sharpener, means for discharging a hot bit therefrom into a tempering bath adapted to receive said bit, and means for automatically interrupting for a desired length of time the movement of said bit towards said bath after said bit is discharged from said machine.

2. The combination comprising a bit

sharpener, means for discharging a hot bit therefrom into a tempering bath adapted to receive said bit, and means for controlling said bit to allow the heat therein to be substantially redistributed for proper tempering before being subjected to said bath.

3. The combination comprising a bit sharpener, means for discharging a hot bit therefrom into a tempering bath adapted to receive said bit, and means for controlling said bit whereby the cutting portion of said bit is subjected to a tempering heat before being subjected to said bath.

4. The combination comprising a bit sharpener, means for discharging a hot bit therefrom into a tempering bath adapted to receive said bit, and means for controlling said bit to allow the heat in the body of said bit to be substantially distributed to the cutting portion thereof to allow proper tempering before being subjected to said bath.

5. A bit sharpening machine comprising bit ejecting means, and means for interrupting movement of said bit after leaving said ejector, and prior to the discharging of said bit from the machine.

6. A bit sharpening machine comprising bit ejecting means, means for interrupting movement of a bit after leaving said ejecting means, and means automatically releasing the bit in accordance with an operation of said machine.

7. A bit sharpening machine comprising bit forming mechanism, bit ejector means, means adapted to interrupt the path of movement of a bit after leaving said ejector, and controlling means for said forming mechanism and common to the control of said interrupting means.

8. A bit sharpening machine comprising bit forming mechanism, bit ejector means, and means adapted to control said bit after leaving said ejector in accordance with operations of other elements of said machine.

9. A bit sharpening machine comprising bit forming mechanism, bit ejector means, and means adapted to automatically control said bit after leaving said ejector in accordance with operations of other elements of said machine.

10. A bit sharpening machine comprising bit forming mechanism, bit ejector means, and means adapted to control said bit after leaving said ejector in accordance with manually controlled operations of other elements of said machine.

11. A bit sharpening machine comprising bit forming mechanism, bit ejector means, a support for ejected bits, and means for controlling the discharge of bits from said support after said bits have remained thereon for an interval of time to allow redistribution of heat from the shank thereof to the bit portion.

12. A bit sharpening machine comprising

bit forming mechanism, bit ejecting means, a discharge chute on to which an ejected bit falls, and a pivotally mounted member disposed in the path of movement of the bits 10 in said chute and movable to control the discharge of a bit therefrom.

18. A bit sharpening machine comprising bit forming mechanism, bit ejecting means,

a discharge chute onto which an ejected bit falls, and a pivotally mounted member disposed in the path of movement of the bits 10 in said chute.

In testimony whereof I affix my signature.

CHARLES M. WEIMER.

Certificate of Correction.

It is hereby certified that Letters Patent No. 1,604,865, granted October 26, 1926, upon the application of Charles M. Weimer, of Brownfield, Pennsylvania, for an improvement in "Bit-Sharpening Machines," were erroneously issued to the inventor, said "Weimer," whereas said Letters Patent should have been issued to *Sullivan Machinery Company, a Corporation of Massachusetts*, said corporation being assignee of the entire interest in said invention, as shown by the records of assignments in this office; and that the said Letters Patent should be read with this correction therein that the same may conform to the record of the case in the Patent Office.

Signed and sealed this 21st day of December, A. D. 1926.

[SEAL.]

M. J. MOORE,
Acting Commissioner of Patents.
